DESIGN FOR A KIDDIE CAR

Joseph L. Schilling, Kearny, N. J.

Application May 31, 1946, Serial No. 130,240

Term of patent 3½ years

(Cl. 34—15)

To all whom it may concern:

Be it known that I, Joseph L. Schilling, a citizen of the United States of America and a resident of the city of Kearny, in the county of Hudson and State of New Jersey, have invented a new, original, and ornamental Design for a Kiddie Car, of which the following is a specification, reference being had to the accompanying drawing, forming a part thereof.

Fig. 2 is a front view thereof.

I claim:

The ornamental design for a kiddie car, substantially as shown.

JOSEPH L. SCHILLING.
